(57) **CLAIM**

I claim the ornamental design for an inflatable racing driver figure, as shown and described.

DESCRIPTION

FIG. 1 is a perspective view of an inflatable racing driver figure showing my new design;

FIG. 2 is a right side view thereof;

FIG. 3 is a top view thereof;

FIG. 4 is a bottom view thereof;

FIG. 5 is a left side view thereof;

FIG. 6 is a front view thereof; and,

FIG. 7 is a rear view thereof.

The broken lines in the drawings are for illustrative purposes only and do not form part of the claimed design.
